CLAIM

The ornamental design for a display screen or portion thereof with animated graphical user interface, as shown and described.

DESCRIPTION

FIG. 1 is a front view of a first image of a display screen or portion thereof with animated graphical user interface showing the claimed design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a perspective view of a kitchen machine having a display screen with the graphical user interface of FIG. 1 applied to the display screen. The graphical user interfaces of FIGS. 2-6 may be similarly applied thereto.

The outermost broken lines in the figures show a display screen or portion thereof, or a kitchen machine having a display screen, and form no part of the claimed design.

The appearance of the images transitions sequentially between the images shown in FIGS. 1-6. The process or period in which one image transitions to another forms no part of the claimed design.
